Primary Examiner—Mimosa De

(74) Attorney, Agent, or Firm—Michael A. Painter

(57) **CLAIM**

The ornamental design for a side chair, as described and shown.

DESCRIPTION

FIG. 1 is front perspective view of a side chair illustrating my new design;

FIG. 2 is a top plan view thereof;

FIG. 3 is a front elevation view thereof;

FIG. 4 is a rear elevation view thereof;

FIG. 5 is a right side elevation view thereof, the left side elevation being identical thereto; and,

FIG. 6 is a bottom plan view thereof.
